UNITED STATES PATENT OFFICE.

HOWARD A. FESSENDEN, OF DETROIT, MICHIGAN, ASSIGNOR TO DETROIT ELECTRIC SIGNAL COMPANY, OF DETROIT, MICHIGAN, A PARTNERSHIP.

SIGNALING APPARATUS.

SPECIFICATION forming part of Letters Patent No. 710,320, dated September 30, 1902.

Application filed September 6, 1901. Serial No. 74,579. (No model.)

To all whom it may concern:

Be it known that I, HOWARD A. FESSENDEN, a citizen of the United States, residing at Detroit, in the county of Wayne and State of Michigan, have invented certain new and useful Improvements in Signaling Apparatus, of which the following is a specification, reference being had therein to the accompanying drawings.

10 The invention relates particularly to electric signal systems of that class wherein a number of distinct signals may be sent from one station to and indicated at another and the transmitted signal returned and indicated at 15 the sending-station, whereby the sender is informed that the particular signal transmitted was properly received.

The invention consists in the novel construction and combination of parts in a system of this type; and it further consists in the peculiar construction of a combined sending and transmitting instrument, as more fully hereinafter described, and shown in the drawings, in which—

25 Figure 1 is a diagrammatic view of the apparatus. Fig. 2 is a sectional view of one of the receiving and transmitting instruments. Fig. 3 is a front elevation, parts being broken away. Fig. 4 is a detail view of the locking mechanism for the signal-operating device, and Fig. 5 is a detail view.

In the drawings thus briefly described the reference-letter A designates a receiving and transmitting instrument at the sending-station, and B is a similar instrument at the receiving-station.

C is a signal-circuit between the instruments, including a circuit breaker and closer, hereinafter described, in the transmitting instrument and a progressively-operating signal in the receiving instrument.

D is a return-signal circuit, by means of which the transmitted message is returned and recorded upon the sending instrument.

45 As the two instruments referred to are of like construction, a description of one only will be given.

The reference-letter E represents a suitable casing having therein a dial-plate F, which 50 may be provided with any ordinary or desirable signal indications, said dial-plate being

protected from dirt and injury by a glass plate G.

H is an annular flange extending about the exterior of the casing, having notches I formed 55 in its periphery opposite to the signal indications marked upon the dial, the function of the notches being hereinafter set forth.

Arranged centrally within the casing and journaled for rotary movement within a framework J is a shaft K, which extends through the glass plate in the manner indicated and carries at its outer free end a signal-operating device, preferably in the form of an operating-arm L. Loosely sleeved upon 65 the shaft within the casing is a circuit breaker and closer P, included within the signal-circuit C, and Q is a yielding connection between the shaft and the circuit breaker and closer, which forms an operative connection between 70 the parts and permits the arm L to be rotated at a greater speed than the circuit breaker and closer. Preferably the latter device consists of a hub a, having a flange b at one end thereof and a disk c at the opposite end, the disk being provided with gear-teeth upon its periphery. Secured to the flange b is a circular plate or disk e, of insulating material, which carries on its periphery an annulus f, 75 having notches g formed therein. 80

h and i are two contacts forming the terminals of the signal-circuit C, which are adapted to bear against the annulus f in the manner indicated in Fig. 4, and j designates a plurality of pins of insulating material arranged within the notched portion of the annulus, for the purpose hereinafter specified.

In front of the dial referred to and mounted for rotary movement upon a common axis with the signal-operating device—viz., the 90 shaft K—is an index R. The index or pointer is fixed to a hub S, sleeved upon the shaft, and is adapted to be actuated progressively by the magnet V, included within the return-signal circuit D. The hub is preferably provided with an annular bearing T and also carries an escapement-wheel U intermediate the bearing and the index. The magnet referred to is arranged within the casing beneath the escapement-wheel, and W is its armature, which carries an escapement engaging 95 the escapement-wheel, as shown in Fig. 2. 100

The operation of the circuit breaker and closer is controlled by the operating-arm L through the agency of stops a' b', arranged upon the shaft and disk c, respectively, one 5 in the path of the other. Thus the rotation of the circuit breaker and closer is limited to the extent of rotation of the operating-arm, and the signal indicated by the latter is enabled to be exactly indicated upon the dial 10 of the indicating instrument. Also means are preferably provided for retarding the operation of the circuit breaker and closer after its actuation by the arm, so that the making and breaking of its circuit would be effected 15 at a speed to insure the proper operation of the index. The means employed comprises a pinion a², journaled in the framework to engage with the teeth upon the periphery of the disk c, an escapement-wheel b², connected 20 to the pinion, and an escapement c², which engages the escapement-wheel, the escapement being mounted on a suitable shaft d², having bearings in the frame. When it is desired to send a signal, the operating device 25 L is rotated by means of the handle Y until the arm is adjacent to the proper indication on the dial. The arm is then held in this position by means of a hook Z, connected to the handle, engaging within the notch in the annular flange H, adjacent to the signal indication, the hook being held in engagement with the notch by means of a spring n, connected 30 to the hook and arm, as shown. The rotary movement of the arm operates the shaft to 35 which it is secured, so as to wind the coiled spring Q to a greater or less extent. The circuit breaker and closer P is in turn revolved by said spring to make and break contact with the terminals h i, the movement of the 40 breaker and closer under the influence of the spring being regulated by the escapement c² and its wheel b². The circuit is complete as long as the contact h is in engagement with the annulus f and breaks as said contact 45 passes over the notches g and insulating pins j in said annulus. This successive making and breaking of the circuit correspondingly energizes the magnet V at the receiving instrument and progressively actuates, step 50 by step, the armature-escapement W and through the medium of its wheel U turns the pointer R. The sending and indicating of the signal having been thus set forth, the operation of returning and indicating the signal 55 upon the transmitting instrument will be obvious, as the instruments are of like construction.

As a matter of precaution a ratchet connection is employed between the signal-operating device or arm and the shaft, so that the latter will not be turned in a direction to unwind a spring and break the parts of the mechanism.

The reference-letter M designates a ratchet-block fixed to the shaft, and O is a spring-impelled pin carried by the arm engaging the ratchet, the means thus described permitting

of the arm being turned independent of the shaft if moved in the wrong direction. I also preferably employ a dog c' upon the 70 framework of each instrument adapted to engage notches d' in the annulus f. The annulus is thus prevented from moving in a direction opposite to that in which it is intended to be driven.

75

It will be noticed from the construction of the mechanism that by mounting the index for rotation upon a common axis with the signal-operating device not only is a more simple and compact instrument obtained, but 80 the operator is enabled to determine at a glance whether the signal transmitted was received and returned. This follows from the fact that the return signal when given causes the index on the sending instrument 85 to move into adjacency or alinement with the signal-operating arm, so that only the arm is visible on the face of the instrument.

What I claim as my invention is—

1. In a signaling apparatus, the combination 90 with a signal-circuit including a signal adapted to operate progressively, of a circuit breaker and closer included in said circuit, an adjustable operating device for the circuit breaker and closer, and connecting instrumentalities 95 between said operating device and said circuit breaker and closer permitting an initial movement of the operating device to the desired extent of its adjustment and a relatively reluctant corresponding movement of the 100 circuit breaker and closer, substantially as described.

2. In a signaling apparatus, the combination 105 with a signal-circuit including a signal adapted to operate progressively, of a circuit breaker and closer included in said circuit, an adjustable operating device for the circuit breaker and closer, connecting instrumentalities between said operating device and said circuit breaker and closer permitting an initial movement of the operating device to the desired 110 extent of its adjustment and a relatively reluctant corresponding movement of the circuit breaker and closer, and means for retarding the operation of the circuit breaker 115 and closer after its actuation has been effected, substantially as described.

3. In a signaling apparatus, the combination 120 with a signal-circuit including a signal adapted to operate progressively, of a circuit breaker and closer included within said circuit, a signal-operating device mounted for movement into different positions of adjustment and adapted to be locked in each of its adjusted 125 positions, a yielding operative connection between said operating device and the circuit closer and breaker and means for retarding the operation of said circuit closer and breaker after its actuation has been effected.

4. In a signaling apparatus, the combination 130 with a signal-circuit including a signal adapted to operate progressively, of a rotatable circuit breaker and closer included within said circuit, a revolute operating-arm adapted to

actuate and control the operation of the circuit breaker and closer, a spring forming a yielding connection between the arm and said circuit breaker and closer, and a lock for retaining the arm in each of its different positions of adjustment.

5. In a signaling apparatus, the combination with a supporting-frame, of a shaft journaled therein, an operating-arm for rotating the shaft in one direction and adapted to move independently of the shaft when turned in the opposite direction, a rotatable circuit breaker and closer loosely sleeved upon the shaft and having a yielding connection with 10 the latter, a progressively-operating signal, and a circuit including the signal and the circuit breaker and closer.

6. In a signaling apparatus, the combination with a supporting-frame, of a shaft journaled 15 therein, an operating device for rotating the shaft in one direction, a rotatable circuit breaker and closer sleeved upon the shaft, a spring connection connecting said circuit breaker and closer with the shaft, a signal adapted to be operated progressively, and a 20 signal-circuit including the signal and the circuit breaker and closer.

7. A signal and return-signal system, including a combined receiving and transmitting instrument provided with a dial, a shaft, 30 an operating device in engagement with the shaft, a signal located at a point remote from said instrument, an operating device for said signal in operative communication with said shaft, an index operable independently of 35 said shaft, and means independent of said signal-operating device for actuating said index, substantially as described.

8. A signal and return-signal system including a combined receiving and transmitting instrument provided with a dial, a shaft, 40 an operating device in engagement with the shaft, a signal located at a point remote from said instrument, an operating device for said signal in operative communication with said 45 shaft, an index operable independently of said shaft, and magnetic devices for actuating said index, substantially as described.

In testimony whereof I affix my signature in presence of two witnesses.

HOWARD A. FESSENDEN.
